SEWING MACHINE CONSTRUCTION

Peter F. Cencer and Fred Whiteman, Detroit,
Mich., assignors to Leonore Gidion, special ad-
ministratrix of the estate of Frank M. Gidion,
deceased

Application October 11, 1950, Serial No. 189,654

6 Claims. (Cl. 112—221)

1

This invention relates to a sewing machine construction, and more particularly to a sewing machine having a novel frame structure of simple construction for mounting thereon a number of the operating parts of the machine.

An object of the present invention is the provision of a sewing machine having a new and improved frame structure for mounting a number of the operating parts.

Another object of the invention is the provision of a sewing machine having a novel frame structure for mounting certain operating parts of the machine effectively on the exterior surfaces of the frame structure, which frame structure is adapted to support a removable housing, whereby when the housing is removed from the frame structure, the operating parts are readily accessible.

Another object is the provision of a frame structure for a sewing machine having such a novel construction that a large number of the operating parts of the machine can be mounted on a single frame member.

Another object of the invention is the provision of a sewing machine frame structure which may be made of stampings, or can be die cast, and having such conformations and interrelation between its elements as to result in a simple though strong mounting means for certain operating parts of the machine.

A further object is the provision of a sewing machine frame structure which includes a plate-like element having certain operating instrumentalities mounted on opposite sides thereof, whereby the instrumentalities cooperate in a novel manner made possible by the novel construction of the frame structure.

Another object is the provision of a sewing machine frame structure made of a plurality of plate-like elements connected together in such a way that they lie in relatively transverse planes, whereby a simple and strong structure results.

A still further object is the provision of a sewing machine frame structure adapted to be enclosed in a removable housing, including a plate-like element arranged with respect to housing so as to divide a portion of the interior of the housing into two chambers, and having certain operating instrumentalities mounted on opposite sides of the plate-like element and in respective chambers, whereby the operating parts are made readily accessible upon removal of the housing from the frame structure.

A further object is the provision of a sewing machine frame structure of simple construction possessing great resistance to vibration.

2

Other objects of the invention will appear upon reference to the following detailed description in conjunction with the accompanying drawings, wherein—

5 Figure 1 is a front elevational view of a sewing machine embodying the present invention including a housing enclosing the frame structure and certain operating parts;

10 Fig. 2 is a front elevational view of the sewing machine with the front portion of the housing removed;

Fig. 3 is a rear elevational view of the sewing machine with the rear part of the housing removed;

15 Fig. 4 is a plan view of the sewing machine with the housing removed;

Fig. 5 is a transverse sectional view taken on line 5—5 of Fig. 2; and

20 Fig. 6 is a view taken from the left end of Fig. 2 with the portion of the housing in the foreground removed and the portion of the housing in the background shown in section.

While the present invention is directed to a sewing machine having a novel frame structure, the drawings illustrate a complete sewing machine for the purpose of bringing out fully the character of the frame structure and its association with certain operating parts.

Certain features of the sewing machine disclosed but not claimed in the present application are disclosed and claimed in the copending application of the present inventors, Serial No. 184,027, filed September 9, 1950.

The sewing machine includes a base 4 in the form of an inverted pan having a top surface 3 or table top 6 and a surrounding skirt portion 8. Foot elements 10 are also provided for engaging the supporting surface on which the sewing machine is placed.

40 The frame structure constituting the principal feature of the present invention comprises two main portions which are indicated generally at 12 and 14. These portions conveniently are formed by two parts secured together to form an effectively integral, unitary structure. A de-
45 scription of the operating parts is combined with the description of the frame structure in order to bring out more fully the nature of the invention.

The frame portion 12 preferably takes the 50 form of a stamping composed of a heavy gauge, sheet metal, plate-like element shaped and formed to have the desired conformations for supporting certain operating parts of the sewing machine. The frame portion 12 includes a 55 transversely disposed, vertical element 16 pro-

vided with a perimeter flange 18 extending at substantially a right angle to the plane of the element 16 and extending around three sides thereof, namely, along the top and downwardly along both vertical edges. The frame portion 12 also includes a foot 20 disposed at a right angle to the element 16 and bearing directly on the top surface of the base, to which it is secured by any convenient means such as screws. The frame portion 12 also includes an upright flange 22 disposed substantially vertically and spaced from the vertical element 16. Strengthening ribs 24 are formed in the foot 20 extending from the vertical element 16 to the upright flange 22.

The frame portion 12 is disposed as a whole adjacent one end of the base, as shown most clearly in Figs. 2 and 4, with the upright flange 22 closely adjacent that end and so positioned that the vertical element 16 is spaced from the flange 22 in a direction longitudinally of the base. It will be noted that the foot 20 is of wide area extent for the purpose of rigidly mounting the frame portion 12, and consequently the complete frame structure, on the base and thereby minimizing vibration. To the end of minimizing vibration and providing the necessary strength for supporting the frame member 14, the vertical element 16 is of considerable transverse width.

An electric motor 26 is mounted on the vertical element 16 of the frame portion 12 by convenient means such as bolts 28. The drive shaft 30 of the motor extends through an aligned aperture in the vertical element 16, and has a driving pinion 32 mounted thereon for rotation therewith. The pinion 32 meshes with a gear 34 secured on a countershaft 36 mounted in bearings in the vertical element 16 and upright flange 22, respectively, the bearings being mounted in apertures therein by any convenient mounting means. The countershaft 36 extends to the right beyond the base of the machine and secured to its outer end is a handwheel 38 provided for the usual purpose. On the inner end of the shaft 36 adjacent the gear 34 is another gear 40 of lesser diameter than the gear 34 which meshes with another gear 42 mounted on a looper shaft 44. The gears 42 and 34 extend through a slot 46 (Fig. 5) in the surface 6 of the base.

The looper shaft 44 is mounted for rotation in bearings 47 and 48 both of which may be formed integral with the base, the former being adjacent the gear 42 and the latter being adjacent a vertical plate 50 extending downwardly from the underside of the base. Also mounted on the plate 50 is a material feeding means 52 for feeding the fabric or other material being sewed through the machine. The details of the material feeding means need not be described in connection with the present invention but a detailed description thereof is found in the Cencer and Whiteman application referred to above.

Mounted on the left end of the looper shaft 44 (Fig. 2) is a cam member 54 in the shape of a cylindrical element mounted eccentrically on the shaft 44. Outwardly of the cam member 54 is a looper 56 which cooperates with the sewing needle in forming stitches in the fabric being sewed.

Mounted on the mounting plate 50 are a pair of feed plates 58 and 60 fitted together with their flat faces abutting and each provided at one end with a slot 62. A screw 64 extends through the slot 62 and is mounted in the mounting plate 50 for affording swinging movement and horizontal movement of the plates 58 and 60.

The plate 58 is provided with a notch 66 and the plate 60 has a horizontally elongated slot 68 both of which receive the cam member 54, the slots being in registration for that purpose. A feed dog 70 is secured to the plate 60, having teeth 72 adapted to be projected up through slots in a throat plate 74 secured over an opening in the top surface of the base.

Pivotedly connected with the free end of the plate 58 is a link 76 secured to a lever 78 pivoted at 80 in the mounting plate 50. The lever 78 has an arcuate slot 82 for receiving one end of a transverse stud mounted on a link 86 pivotally connected with the free end of plate 60. Upon horizontal reciprocation of the plate 58 by the action of the cam 54 in the slot 66, the lever 78 is swung, which in turn acting through link 86 reciprocates the plate 60 in a horizontal direction. The cam 54 acting in the slot 68 reciprocates the plate 60 vertically and the combined horizontal and vertical reciprocation of the plate 60 causes the feed dog 70 to extend up through the slots in the plate 74 and move horizontally toward feeding the fabric or other material through the machine.

A U-shaped link or yoke 88 has legs straddling the three elements, namely, mounting plate 50 and plates 58 and 60, with one leg pivoted on the mounting plate 50 and the other leg provided with a slot 90 receiving one end of a transverse pin 92 fixed to the link 86. Upon vertical swinging of the yoke 88 the pin 92 is moved closer to or farther from the pivot point 80 of the lever 78 for varying the extent of horizontal movement of plate 60 and consequently of the feed dog 70.

The means for swinging the yoke 88 includes horizontal arms 94 on the yoke (Fig. 2) which receive one arm 96 of a bell crank lever, the other arm 98 being pivotally connected to a rod 100, the opposite end of which is provided with a screw and adjusting knob 102, the screw being slidable in a slot in the base and the knob being adapted for turning down and clamping with respect to the base for securing the rod 100 in adjusted position.

The frame portion 14, similarly to the portion 12, preferably is made up of a single piece in the form of a stamping, being formed from a flat plate-like element. The frame portion 14 includes a vertically disposed plate-like portion 104 having a reinforcing flange 106 along its lower horizontal edge and a reinforcing flange 108 along its upper horizontal edge. One end of the plate-like portion 104 is provided with an outturned flange 110 abutted against the vertical element 16 of the frame portion 12 and secured thereto, preferably by spot welding. Similarly the lower flange 106 is provided with a downturned terminal flange 112 abutted against the vertical element 16 and also rigidly and permanently secured thereto as by means of spot welding. Likewise the upper flange 108 has an extension 114 secured to the perimeter flange 18 and in this case also the securement preferably is made by means of welding. It will be seen that an effectively rigid and secure connection is made between the frame portions 14 and 12 for the purpose of providing a strong frame structure and minimizing vibration.

The frame portion 14 is positioned at the upper end of the vertical element 16 and accordingly is elevated in spaced relation with respect to the base, extending horizontally longitudinally of the base to a position adjacent the opposite end. The extended end of the frame portion 14

and particularly the portion 104 thereof has a vertically extending flange 116 (Figs. 3 and 4).

A rock bar 118 which preferably takes the form of a stamping made up from an originally flat strip or strap and shaped to have laterally extending arms 120 and 122, is mounted on the frame element 14. The rock bar is disposed with its main portion on one side of the frame portion 14 with the arm 120 extending through an aperture 124 formed by stamping a lug 126 therefrom which extends transversely of the frame member. The arm 120 is pivotally mounted at a point intermediate its ends in the lug 126 as by means of a rivet and the extended end of the arm 120 is connected with a pitman 128, the lower end of which is eccentrically pivoted on the gear 40. The arm 122 is pivotally mounted intermediate its ends in the transverse flange 116 with the extended end of the arm on the side of the frame portion 14 opposite the main portion of the rock bar. The extended end of the arm 122 is provided with a thread aperture 130 (Fig. 6). The arm 122 is operative for actuating the needle bar, as will be described presently.

The needle bar 132 referred to is vertically reciprocally mounted in bearing sleeves 134 and 136, the sleeve 134 being supported on a horizontal plate-like element 138 which is preferably a separate piece of heavy gauge material secured to a horizontally bent extension of the frame portion 14, the two elements together having great strength. The sleeve 136 depends vertically from a plate element 140 secured to a horizontal flange 142 as by welding, the flange 142 being an integral extension of the frame portion 14. A sewing needle 144 having the usual eye is mounted in the lower end of the needle bar by means of a screw 146. A stud 148 is fixedly secured to the needle bar 132. A pitman 150 has its lower end pivotally connected with the stud 148 and its upper end pivotally connected with the arm 122 at the point on the latter spaced inwardly from the swinging end of the arm and from the aperture 130. The rock bar 118 is adapted to be rocked upon operation of the motor 128 acting through pinion 32, gear 34, gear 40 and pitman 128; rocking of the rock bar swings the extended end of the arm 122 which in turn reciprocates the needle bar and needle.

The extended end (i. e., left end) of the frame portion 14 also supports a vertically reciprocable presser foot 152 which is supported on the lower end of a presser foot bar 154, which is vertically reciprocable in bearing sleeves 156 and 158. The sleeve 156 is secured to the plate element 138 and the sleeve 158 is secured to the upper plate element 140. Secured to the presser foot bar 154 is a collar 160 positioned above the plate element 138. A compression spring 162 surrounds the presser foot bar between the collar 160 and the bearing sleeve 158, urging the presser foot downwardly. A camming lever 164 is pivotally mounted on a pin extending from the collar 160, having camming surfaces which upon upward swinging of the lever 164 engage the plate element 138 in such manner as to raise the presser foot bar and presser foot. The camming lever 164 also has a surface for retaining the lever in over-center position for holding the presser foot in elevated position. It will be understood that the presser foot is raised for the purpose of inserting material to be sewed under the presser foot, and then let down for the purpose of holding and guiding the material being sewed.

As observed in Fig. 6, the plate elements 138 and 140 have substantial transverse dimensions

for the purpose of mounting the needle bar 132 and presser foot bar 154. The portions of the frame portion 14 supporting the plate elements 138 and 140 also have the desired transverse dimensions for rigidly mounting the plate elements 138 and 140.

The element 104 of the frame portion 14 is provided with an aperture 166 for receiving a thread spool 168. The spool 168 is placed on a spindle 170 pivotally mounted on a lug 172, stamped out from the vertical element 104, for horizontal swinging of the spindle. The spindle may be swung away from the frame member for the purpose of placing the spool thereon, after which it is swung back for carrying the spool into the aperture in such position that portions of the spool extend outwardly from opposite sides of the frame member. The swinging end of the spindle 170 engages the marginal edge of the aperture whereby the spool is properly positioned in the aperture.

The thread 172 from the spool is threaded through a series of guide fingers 174 which are in the form of wires each having one end secured to the frame member and a loop formed in the extended end. The thread is threaded through the loops in feeding the thread to the sewing needle. A pull-off finger 176 is disposed between certain of the guide fingers 174 and is of similar construction to the guide fingers. The pull-off finger 176 is secured to the rock bar 118 and extends through an aperture 178 in the frame member 14 and also has a loop in its extended end through which the thread is threaded. Upon rocking of the rock bar, the pull-off finger 176 is swung vertically for the purpose of paying out thread from the spool. It will be noted that the pull-off finger extends through the frame member and terminates on the opposite side thereof adjacent the extended ends of the guide fingers.

Posterior to the guide fingers 174 with respect to feeding the thread toward the sewing needle is a tensioning means 180 which includes a threaded shank 182 (Fig. 4) on the outer end of which is a head or knob 184. Surrounding the shank 182 is a compression spring 186, one end of which bears on the frame member and the other end bears on the adjacent one of a pair of disks 188 loosely mounted on the shank 182. The disks 188 are urged against the knob 184 by the action of the spring, the disks having convex peripheral portions facing each other for permitting easy insertion of the thread between the disks, the compression spring 186 then causes a gripping force on the thread by the disks. The shank 182 is adjustable in the frame member for the purpose of adjusting the compression on the spring 186 and thereby adjusting the gripping action on the thread. It will be noted that the tensioning means 180 is disposed on the same side of the frame member as the guide fingers 174.

Posterior to the tensioning means 180 is a thread nipper 190 which includes a sleeve 192 threaded in an aperture in the frame member 14 for adjustment therein. The extended end of the sleeve 192 is provided with a nut-like element 194 and slidably in the sleeve is a shank 196 having a knob 198 on its end. A compression spring 200 surrounds the shank 196 in the sleeve, one end of the spring engaging a washer 202 fixed to the shank and the other end engaging the nut-like element 194. The thread nipper 190 is effectively disposed on the same

side of the frame portion 14 as the tensioning means 180 while the end of the shank 196 projects through the frame portion 14 and is engageable by a bumper 204, preferably of rubber-like material, secured to the rock bar 118. The compression spring 200 urges the knob 198 toward the nut element 194 for nipping or gripping the thread therebetween and upon downward rocking of the rock bar 118 the bumper 204 engages the shank 196 and carries the head or knob 198 out of gripping relation with respect to the thread.

The thread is then threaded through the aperture 130 in the arm 122 and then through an aperture 206 in the plate element 138 and finally 15 through the eye of the needle.

Reference is made to the above mentioned Cencer and Whiteman application for a complete discussion of the operation of the sewing mechanism of the machine.

It will be seen from the above that all of the operating parts that are located above the base of the machine are mounted on the unitary frame structure hereinabove described. The frame structure is essentially of solid construction, that is, it does not have any internal cavities in which any of the operating parts are hidden or made inaccessible. All of the operating parts are disposed on the frame structure such that they are effectively on the exterior thereof.

In view of the foregoing detailed description, and by way of summary, the following advantages of the invention are here pointed out: (a) the frame is simple and easy to make; (b) the frame is rigid, whereby vibration is effectively eliminated; (c) mounting of a substantial number of operating parts on the frame is made simple and convenient; (d) the operating parts are maintained in predetermined relation without adjustment or change in interrelation; and (e) all of the operating parts mounted on the frame are made fully accessible (after removal of one or more sections of the housing).

The following specific arrangements are to be noted in connection with the simplicity of the frame structure and the mounting of the operating parts thereon: the rock bar is disposed bodily on one side of the frame member with its arms extended through to the opposite side where they actuate various instrumentalities. The pull-off finger 176 has one end mounted in the rock bar and its swinging end extends through the frame member to the opposite side thereof where it is adjacent the guide fingers 174. The tensioning means 180 and the nipper 190 are effectively mounted on one side of the frame member and in the case of the nipper a portion extends through to the opposite side where it is engaged by the rock bar.

The frame structure is of simple construction, being stamped from flat stock and shaped in such a manner as to impart unusual strength and rigidity thereto. Vibration due to the movement of the operating parts is effectively eliminated.

For the purpose of protecting the operator and producing a finished appearance to the sewing machine a housing, indicated generally at 208, is provided for enclosing the frame structure and substantially all of the operating parts thereon. The housing 208 includes a section 210 on one side of the frame structure and two sections 212 and 214 on the opposite side. The three sections together totally enclose the frame structure and the parts mounted thereon with the exception 75

of the handwheel 38 and the lower ends of the needle and needle bar, and presser foot and presser foot bar. The section 210 is secured at one end to the base as by means of screws and at the opposite end to the extended end of the horizontal frame member 14. The section 212 is also secured to the base as by means of screws, while the section 214 is supported by the other two sections. The means for supporting the section 214 includes a strip 216 overlying the parting line between the sections on opposite sides of the machine and secured to the section 210. The section 214 is fitted under the strip 216 and is provided with a spring clip which enters into the aperture 218 in the frame member 14. The section 214 is readily removable merely by grasping it and pulling outwardly on it, so that the operator can easily gain access to that portion of the frame structure and the parts carried thereby; the other two sections can be removed after removing the securing screws.

The structure of the frame structure, together with the novel mounting of the operating parts thereon, produces an arrangement whereby the operating parts are readily entirely enclosed by the housing while they are made readily accessible to the operator after removing one of the sections, or all of the sections, of the housing. So far as we are aware it is entirely new to mount all of the operating parts such as those above the base of the machine on the exterior of a frame structure in such a manner that they are readily accessible, and whereby they can be readily enclosed by an enclosing housing which surrounds the entire frame structure and the operating parts thereon and does not form a part of the frame structure itself. A further advantage is thus to be noted: none of the operating parts are attached to or carried by the housing; the housing is removable without disturbing any of the operating parts.

While we have herein shown and described a certain preferred embodiment of the invention, it will be understood that changes may be made therein within the scope of the appended claims.

We claim:

1. In a sewing machine, a base, a frame including a portion having a horizontal foot secured to the base, a transversely disposed, vertical plate-like flange secured to and extending upwardly from said foot portion and positioned closely adjacent one end of the base, and a transversely disposed, vertical plate-like portion secured to and extending upwardly from said foot portion and positioned adjacent to but spaced from said end of the base, the frame also including a horizontally extending plate-like portion secured to and extending from said vertical portion in elevated spaced relation with respect to the base and extending longitudinally of the base, said horizontal frame portion being positioned with its flat sides disposed vertically, a plurality of operating parts mounted on said vertical frame portion with cooperating elements of the operating parts on opposite sides thereof, and a plurality of operating parts mounted on said horizontal frame portion with cooperating elements of the operating parts on opposite sides thereof, and a housing enclosing the frame and operating parts in disconnected relation to the operating parts.

2. In a sewing machine, a base, a frame portion comprising a unitary, flat member shaped to have a plate-like foot secured to the base, a transversely disposed, vertical flange secured to and extending upwardly from the foot and positioned

adjacent one end of the base, and a transversely disposed vertical portion secured to and extending upwardly from said foot and spaced from said flange longitudinally of the base, said vertical portion having a perimeter reinforcing flange disposed transversely of its plane, and a horizontal plate-like portion having a transverse member secured to said vertical portion, said horizontal frame portion being in elevated spaced relation with respect to the base and extending longitudinally thereof, said horizontal frame portion having its flat sides disposed vertically and having a transverse reinforcing flange along one horizontally extending edge.

3. In a sewing machine having a base, a frame including an upright portion mounted on the base adjacent one end thereof, a horizontal portion secured to said upright portion in elevated spaced relation with respect to the base and extending longitudinally thereof, said horizontal frame portion being plate-like in form with its flat sides disposed vertically, said horizontal frame portion having an aperture therethrough, and a spindle mounted on said horizontal frame portion movable into and out of position in which a spool placed on the spindle is disposed in the aperture with a portion of the spool extending outwardly from each side of the frame.

4. In a sewing machine having a base, a frame mounted on the base including a vertical, transverse plate-like portion secured to the base and a horizontal portion secured to the upper end of the vertical portion and extending longitudinally of the base and having its extended end unsupported, said horizontal portion being of plate-like form and having its flat sides disposed vertically, the extended end of said horizontal frame portion having a pair of vertically spaced, horizontally extending plates, a sewing needle bar reciprocably mounted in said plates, a rock bar rockably mounted on said horizontal frame portion having operative connection with said needle bar, and driving means mounted on the frame having operative connection with said rock bar.

5. In a sewing machine having a base, a frame mounted on the base including a vertical, transverse plate-like portion secured to the base and a horizontal portion secured to the upper end of the vertical portion and extending longitudi-

nally of the base and having its extended end unsupported, said horizontal portion being of plate-like form and having its flat sides disposed vertically, the extended end of said horizontal frame portion having a pair of vertically spaced, horizontally extending plates, a presser foot bar reciprocably mounted in said plates, a cam lever pivotally mounted on said presser foot bar, said cam lever having camming surfaces engageable with one of said plates whereby upon swinging of said lever said camming surfaces engage the plate for raising the presser foot bar, a sewing needle bar reciprocably mounted in said plates, a rock bar rockably mounted on said horizontal frame portion having operative connection with said needle bar, and driving means mounted on the frame having operative connection with said rock bar.

6. A frame for a sewing machine having a base, said frame comprising, a first portion composed of a flat plate-like element shaped to have a foot for securing to the base, a vertical portion secured to and extending upwardly from said foot and having a reinforcing perimeter flange disposed transverse to its plane, and an upright flange secured to and extending upwardly from said foot and spaced from and parallel to said vertical portion, said frame also including a second portion composed of a horizontal portion mounted on the upper end of said vertical portion, said horizontal frame portion being in the form of a flat plate-like element having its flat sides disposed vertically and shaped to have a reinforcing flange along its top edge and along its bottom edge, said plate-like element of the horizontal portion and one of the reinforcing flanges thereon having transverse flanges abutting against and secured to said vertical frame portion.

PETER F. CENCER.
FRED WHITEMAN.
